UNITED STATES PATENT OFFICE.

MELCHIOR ZWICKY, OF SPRING TOWNSHIP, BERKS COUNTY, PENNSYLVANIA, AS
SIGNOR TO TEXTILE MACHINE WORKS, OF WYOMISSING, PENNSYLVANIA, A COR-
PORATION OF PENNSYLVANIA.

CROSSBAR CHAIN.

Application filed August 22, 1924. Serial No. 733,491.

To all whom it may concern:

Be it known that I, MELCHIOR ZWICKY, a citizen of the United States, residing in Spring Township, in the county of Berks 5 and State of Pennsylvania, have invented certain new and useful Improvements in Crossbar Chains, of which the following is a specification.

My invention relates to chains having parallel crossbars with end link connections; and my main objects are, first to provide an improved chain of this type which will be so limitedly flexible as to permit of its passing freely around an engaging wheel 15 while at the same time avoiding an undesired degree of such flexibility and securing substantial lateral rigidity; and second to provide a simple and advantageously novel chain construction of this type. The invention is fully described in connection with the accompanying drawings illustrating an embodiment thereof in which the cross-bars are adapted for the desired securing of pattern-controlling lugs; and the novel features are clearly defined in the claims.

Fig. 1 is a partly sectional plan view of a portion of flattened-out chain embodying my invention; the flat crossbars indicated being shown apertured for the convenient 30 securing of pattern lugs, and a cross-sectional view of one of these being also shown.

Fig. 2 is an end view showing a portion of the chain bent around an engaging drive wheel indicated, with an end thereof extending straight; certain of the crossbars being omitted to clearly show the link aperture; and others being shown in cross-section on the line 2—2 of Fig. 1, or in end view with indication of the riveting shown 40 in Fig. 1 for retaining the links on the engaged bar.

Fig. 2 of the drawing indicates a toothed drive wheel around which my improved chain is bent as permitted by the novel construction; such bending however being represented as approximately the maximum allowed by the link and crossbar connections shown, so that when free from the wheel the chain will fold only to about the same degree and be free of objectionable contact of the links and crossbars forming the same. The parallel crossbars shown are adapted, by means of the series of screw-threaded apertures B shown therein, to permit of easy

application as required, of pattern lugs C 55 such as are commonly employed in textile machinery in connection with a drive wheel as indicated.

The crossbars 10, 10, as indicated, are conveniently formed generally of rolled metal of desired cross-section, as one-half inch wide by one-eighth inch thick and of any determined length, with connecting-end portions 11 of reduced width forming shoulders 12, 12; the opposite edge portions 13, 13 of these connecting ends being curved in cross-section, as shown, to a radius equal to one half the width thereof, and the centre line of the bar being an axis of rotation thereof in the connecting links 15. 70

Each of these links 15, as shown, may be formed from a short flat bar provided with connecting apertures 16, 16 spaced apart so as to desirably space the crossbars 10, 10. Each of these link apertures corresponds in longitudinal extent with the width of the connecting-end portions 11 of the crossbars, and its end walls 17, 17 are curved, as shown, to the same radius as the edge portions 13, 13 of the latter. Thus no longitudinal movement of the bar is allowed in an engaged link; but a limited rotary movement of the bar on its axis is permitted in the engaged link by making each aperture 16 determinedly wider than the thickness of the engaged bar end 11, as clearly shown in Fig. 2; thus giving the chain sufficient flexibility to permit of its freely curving around wheel A with the curved edges 13 of the connecting end portions 11 of the bar always in 90 sliding contact with the similarly curved walls 17 of the link apertures, but with the flexibility definitely limited as determined by the width of the link apertures relative to the thickness of the engaged bar 95 ends. This functioning feature of my improved chain is of practical importance for many uses, and its novel construction is very simple and advantageous.

What I claim is:

1. A cross-bar chain having a limited linking flexibility; comprising a series of cross-bars having shouldered flat ends and opposed series of overlapped connecting links; each link being provided with engaging apertures corresponding in longitudinal extent with the width of said flat ends and exceeding in lateral extent the thickness of the

latter, and overlapping portions of adjacent links being loosely retained upon a flat end of each crossbar.

2. A cross-bar chain having a limited linking flexibility; comprising a series of cross-bars having shouldered flat ends and opposed series of overlapped connecting links; each link being provided with engaging apertures corresponding in longitudinal ex-

tent with the width of said flat ends and exceeding in lateral extent the thickness of the latter; the end walls of said link apertures and the side edges of said bar ends being concentrically curved, and overlapping portions of adjacent links being loosely retained upon each bar end.

In testimony whereof I affix my signature.
MELCHIOR ZWICKY.
